UNITED STATES PATENT OFFICE

2,477,719

CLOSURE ACTUATOR FOR CONTAINERS

Robert J. Byrd, Chicago, Ill.

Application August 1, 1947, Serial No. 765,817

5 Claims. (Cl. 312—192)

1

This invention relates to an improved construction of closure actuator for containers and more particularly has reference to a structure for normally retaining a closure or lid of a container in an open position and for preventing the lid from accidentally swinging to a closed position.

More particularly, the present invention is particularly intended and adapted for use in conjunction with or as a part of a shoe shine kit for providing a lid or closure which will not be jarred to a closed position by vibration of the kit or container, when in an open position and in use.

Still a further object of the invention is to provide a device for yieldably retaining a container closure or lid in an open position and substantially at a right angle to the open top of the body of the container and which will effectively function to prevent accidental closing thereof.

Various other objects and advantages of the invention will hereinafter become more fully apparent from the following description of the drawings, illustrating a preferred embodiment thereof, and wherein:

Figure 1 is a top plan view, partly broken away showing a shoe shine kit or container constructed in accordance with the invention;

Figures 2 and 2A are longitudinal sectional views taken substantially along planes as indicated by the lines 2—2 and 2A—2A of Figure 1, respectively;

Figure 3 is a cross sectional view of the kit or container taken substantially along a plane as indicated by the line 3—3 of Figure 2;

Figure 4 is a fragmentary cross sectional view thereof taken substantially along a plane as indicated by the line 4—4 of Figure 2A;

Figure 5 is a fragmentary longitudinal sectional view, similar to Figure 2 but showing the lid in an open position;

Figure 6 is a horizontal sectional view taken substantially along a plane as indicated by the line 6—6 of Figure 5;

Figure 7 is a transverse sectional view taken substantially along a plane as indicated by the line 7—7 of Figure 5, and

Figure 8 is a fragmentary front elevational view of the kit or container in a closed and latched position.

Referring more specifically to the drawings, wherein the invention has been illustrated in conjunction with a shoe shine kit or container, said container in its entirety is designated generally 10 and is formed of two sections 11 and 12 of substantially corresponding size disposed with their

open, inner sides in abutting engagement when the container 10 is closed.

While the container 10 has been illustrated and described as being formed of the bottom or body section 11 and the lid or top section 12, both of substantially the same depth, it will be readily apparent as the description proceeds that the lid or top section 12 could, without affecting the invention, be of a depth substantially less than the bottom section 11 and it will likewise be readily apparent that the invention is equally well adapted to other uses than shoe shine kits or containers, such as in providing a means for yieldably retaining the lid of a trunk, chest or similar container in an open position unless the lid is latched or locked in a closed position, to thereby prevent the lid from accidentally falling from an open toward a closed position and possibly causing bodily injury.

20 The upper section 12 is connected by hinges 13 to the body section 11 externally thereof and along one end, as clearly illustrated in Figure 1, but said lid 12 could be hinged equally well along a side thereof to the body 11.

25 The body and lid sections 11 and 12, respectively, preferably include side and end walls 14 which are attached to an external covering 15 which may extend around the sides and also across the bottom of the section 11 and the top 30 of the section 12. The body section 11 is provided with a secondary, internal end wall 16 which is secured to the inner side of the end wall 14 thereof located adjacent the hinges 13 and which extends above the open top of the body section 11 into the lid-section 12. Said end wall 14 of the body section 11 is provided with spaced 35 upwardly and inwardly opening recesses 17, as best seen in Figure 3, and the wall 16 is provided with an internal recess 18 which extends substantially from side to side and from top to bottom thereof and is also provided with openings 19 forming communicating passages between said recess 18 and the recesses 17.

In the embodiment of the invention as disclosed, the opposite end wall 14 has a post 20 secured by fastenings 21 to the inner side thereof and which likewise rises into the lid section 12. One end of a foot rest 22 is suitably secured to the upper end of the post 20 and the opposite end 40 of said foot rest 22 is suitably secured in a notch or recess 23 to the upper edge of the wall 16.

The end wall 14 of the lid section 12, disposed adjacent the hinges 13, has a plurality of rods 24 anchored therein. Each of the rods 24 has a lower end which extends into one of the recesses 17,

when the lid 12 is closed, and said lower ends of the rods 24 terminate in eyes 25. The eye of the intermediate rod 24 is connected to one end of a contractile coiled spring 26 which, as best seen in Figures 2 and 4, extends therefrom upwardly through the intermediate passage 19, upwardly in the recess 18 of the wall 16, through a transverse passage 27 in the upper portion of said wall 16 and into a recess 28 of the foot rest 22, in which the opposite end of said spring 26 is anchored at 29. The eyes 25 of the two outermost rods 24 are each connected to an end of a contractile coiled spring 30 and said springs extend therefrom through the complementary passages 19 into the recess 18 and connect at their opposite ends to the depending ends of contractile coiled springs 31 which are anchored at their upper ends by eye fastenings 32 to the wall 16 and within the recess 18 thereof. Two springs 30 and 31 are employed instead of a single spring due to the fact that the springs 30, 31 converge upwardly but, if desired, the spring means 30, 31 could be disposed parallel to another and to the spring 26 and in such case could be formed from a single spring. Likewise, if desired, the spring 26 could be anchored in the recess 18 to an eye fastening 32, as are the springs 31.

As seen in Figures 1 and 2, the top of the lid or closure section 12 is provided with a pivotally mounted handle 33 and a latch means 34, of conventional construction, is associated with the free end walls of said sections 11 and 12 for latching the lid section 12 in a closed position on the body section 11, as illustrated in Figures 1 and 2.

To open the lid 12, it is only necessary to disengage the latch 34 to permit the springs 26 and 30, 31 to retract for pulling the lower ends of the rods 24, to which they are connected, inwardly and upwardly of the container 10 through the passages 19 from the recesses 17 into the recess 16 for swinging the lid-section 12 counterclockwise from its position of Figure 2, to its open position of Figure 5. It will be noted that the openings or passages 19 extend to above the recesses 17 and the upper ends thereof form stops for engagement with the rods 24 for limiting the opening swinging movement of the lid section 12 to prevent it from swinging past a substantially vertical or upright position, as seen in Figures 5 and 6. When the lid 12 is fully opened, as seen in Figure 5, the springs 30, 31 will assume substantially the positions of Figure 7.

It will be readily obvious that the shoe shine kit 10 may be utilized for shining shoes, when in an open position by resting either foot on the foot rest 22 while the shoe is shined, and the body portion 11 will afford a storage space for shoe polishes, brushes and the like, not shown.

Various modifications and changes, in addition to those previously referred to, are contemplated and may obviously be resorted to, without depart-

ing from the spirit or scope of the invention as hereinafter defined by the appended claims.

I claim as my invention:

1. In a lid actuator for containers having hinged, recessed lids, a rod anchored in the lid adjacent its hinged edge and extending into a portion of the body of the container, said container body having an interior portion rising above the open top thereof and having an upper part normally disposed within the lid when the latter is in a closed position, resilient means anchored to said interior portion adjacent the top thereof and connected to the lower end of said rod for urging said rod upwardly and inwardly with respect to the container for normally urging the lid toward an open position.

2. An actuator for container closures as in claim 1, and said interior portion of the body having a stop portion for engagement with said rod for limiting the movement of the lid toward an open position.

3. An actuator for container closures as in claim 1, and said interior portion of the body having a stop portion for engagement with said rod for limiting the movement of the lid toward an open position and for combining with said resilient means for normally retaining the lid at substantially a right angle to the container body.

4. In a closure actuator for containers having recessed lids, a container body, a closure hinged thereto along one edge thereof, an internal wall in said container body extending into the closure when the latter is in a closed position, a plurality of rods anchored to the lid along its hinged edge and extending downwardly into the container body when the lid is in a closed position, and resilient means anchored to the upper portion of said internal wall of the container body and connected to the lower ends of said rods for normally urging the lid toward an open position.

5. A container lid actuator as in claim 4, and said internal wall having stop means engageable by said rods for limiting the opening movement of the lid in response to said resilient means.
